COMBINED SHOE TREE AND SHOE HORN

Karl Conradi, Lattingtown, N. Y.

Application February 15, 1955, Serial No. 34,524

Term of patent 14 years

(Cl. D7—1)

Figure 1 is a view in side elevation of the combined shoe tree and shoe horn.

Figure 2 is a bottom plan view of the combined shoe tree and shoe horn.

Figure 3 is a cross sectional view taken on line 3—3 of Figure 1.

Figure 4 is a fragmentary view of the shoe horn portion of the present invention, in position for use.

I claim:

The ornamental design for a combined shoe tree and shoe horn, substantially as shown and described.
